GRINDING WHEEL TRUING APPARATUS

George E. Hulbert, Westboro, Mass., assignor to
Norton Company, Worcester, Mass., a corpora-
tion of Massachusetts

Application August 7, 1935, Serial No. 35,121

7 Claims. (CL. 125—11)

This invention relates to grinding machines, and more particularly to a grinding wheel truing apparatus for truing the operative face of a grinding wheel.

5 One of the objects of this invention is to provide a simple, thoroughly practicable grinding wheel truing apparatus for truing the operative face of a grinding wheel.

Another object of this invention is to provide 10 a truing apparatus of a simple and rugged construction which enables the truing of the side face of a grinding wheel.

It is another object of this invention to provide 15 a truing apparatus which is arranged to true the two opposed operative side faces of a grinding wheel.

Another object of this invention is to provide 20 a simplified truing apparatus with which the opposed operative side faces as well as the peripheral face of the grinding wheel may be accurately trued.

Other objects will be in part obvious or in 25 part pointed out hereinafter.

This invention accordingly consists in the features of construction, combinations of elements, and arrangements of parts as will be exemplified in the structure to be hereinafter described, and the scope of the application of which will be indicated in the following claims.

30 In the accompanying drawing in which is shown one of the various possible embodiments of the mechanical features of this invention,

Fig. 1 is a fragmentary front elevation of a 35 grinding machine showing the improved truing apparatus in operative position to true the side face of the grinding wheel; and

Fig. 2 is a fragmentary cross sectional view showing the truing apparatus in position for truing the peripheral surface of the grinding wheel.

40 The embodiment of the invention selected for illustration comprises a grinding machine having a base 10 which supports a longitudinally movable work supporting table 11 on the usual V-way 12 and flat way 13.

45 A rotatable grinding wheel 14 is supported on a wheel spindle 15 which is rotatably journaled in a wheel slide 16. The wheel slide 16 is arranged for a transverse movement relative to the base 10 and is supported thereon by ways.

50 17. The slide 16 may be moved transversely relative to the base by a feeding mechanism which comprises a depending half nut 18 on the slide 16 which meshes with a rotatable feed screw 19 rotatably supported in bearings 20 in the base 10 of the machine. The front end of the

screw 19 is provided with a gear 21 meshing with a gear 22 mounted on the inner end of a rotatable shaft 23. The shaft 23 may be rotated, either manually or by power, by any well-known wheel feeding mechanism such as, for example, that shown in the expired U. S. patent to Norton No. 762,838 dated June 14, 1904. The feed mechanism serves when rotated to turn the cross feed screw 19 and cause a transverse movement of the grinding wheel 14 either toward or from the work supporting table 11.

5 10 The table 11 is provided with a rotatable work support for rotatably supporting the opposite ends of a work piece to rotate the same while grinding a peripheral portion thereof. Such a work rotating mechanism may comprise a head and footstock center (not shown), such as that shown in the above-mentioned prior patent to Norton. In the embodiment selected for illustration, however, the work table is provided with a pair of opposed work supporting heads 30 and 31 having rotatable spindles 32 and 33 which in turn support rotary work holders 34 and 35 respectively. The work holders 34 and 35 are arranged to support the opposite ends of a work piece and are provided with clamping members 36 and 37 which serve to rigidly clamp a work piece in operating position on the machine. The details of construction of the work supporting heads 30 and 31 and the work holders 34 and 35 have not been illustrated in the present case, 15 since these are not considered parts of the present invention. For further details of the construction of the head and work holders, reference may be had to the prior patent to Silven, et al. No. 1,837,342 dated December 22, 1931.

20 The work table 11 is slidably mounted on the ways 12 and 13 of base 10 to permit a longitudinal movement of the work piece relative to the grinding wheel to position the work in the desired relation with the operative face of the grinding wheel. A manually operable mechanism is provided for moving the table 11 longitudinally relative to the base 10. This mechanism comprises a rack bar 38 depending from the table 11. The rack 38 meshes with a gear 39 which is mounted on the inner end of a rotatable shaft 40. The shaft 39 also supports a gear 40 which meshes with a gear 41 mounted on the inner end of a rotatable shaft 42. The outer end of shaft 42 is provided with a manually operable hand wheel 43 which serves through the train of gears and rack, above described, to cause a longitudinal positioning movement of the table 11 relative to the grinding wheel 14.

In the grinding of work pieces, such as crankpins on a multiple throw crankshaft, it is necessary not only to grind the cylindrical body of the crankpin to the desired size and finish but it is also necessary to grind the cheeks or side end faces adjacent to the ends of the crankpin so that the distance between the cheeks comes within the required limits. To accomplish this result, it is desirable to provide a grinding wheel with an operative peripheral surface for grinding the body or cylindrical portion of the crankpin and to provide such a wheel of a thickness which will grind the cheeks of the pin to the required dimensions. It is accordingly desirable to provide a truing apparatus for not only truing the periphery of the grinding wheel but which is adapted to also true one or both side faces thereof to true the wheel to the required thickness to produce the crankpin and cheeks of the required dimensions. In the embodiment of the invention illustrated, this apparatus comprises a supporting shaft 50 which as illustrated in the drawing has its opposite ends clamped rigidly in the work heads 34 and 35 by means of the work clamps 36 and 37. A rotatable sleeve 51 is rotatably supported on the shaft 50 and is held in an adjusted longitudinal position thereon by means of a flange 52 which is formed as an integral part of the shaft 50. The sleeve 51 is held in place on the shaft 50 in the proper relation with the fixed flange 52 by means of an adjustable collar 53 which is adjustably supported on the other end of shaft 50 by means of a threaded portion 54.

The sleeve 51 is provided with upwardly extending bosses 55 and 56 each of which is provided with an aperture 57 and 58 respectively which are arranged with their axes at right angles to the axis of the sleeve 51 and shaft 50. A truing tool holder 59 and 60 are supported in the apertures 57 and 58 and locked in adjusted position relative thereto by means of clamping screws 61 and 62 respectively. The outer ends of the holders 59 and 60 serve to adjustably support a truing tool, such as a diamond truing tool 65 and 66 respectively which are held in adjusted position thereon by clamping screws 67 and 68 so that the truing tools or diamonds may be readily removed and replaced when desired or adjusted relative to the holders.

The manually operable lever 75 is provided to rock the sleeve 51 relative to the shaft 50 so as to swing the diamonds 65 or 66 in an arcuate path across a portion of the opposite side face of the grinding wheel 14. The lever 75 is connected to an adjustable collar 76 which surrounds the sleeve 51. The collar 76 is provided with a central aperture 77 which snugly fits the outer diameter of the sleeve 51 and is preferably split as shown at 78 and arranged to be clamped in adjusted position on sleeve 51 by means of a screw 79. To true either side face of the grinding wheel, the lever 75 is rocked in a clockwise direction, as indicated in Fig. 2, from position 75 into position 75a, which serves to swing the truing tool from position 65 into position 65a, thereby swinging the diamond in an arcuate path across a portion of the side face of the grinding wheel 14.

An adjustable stop 85 is provided to limit the movement of the lever 75 in one direction. The stop 85 is adjustably supported on a base member 86 which is provided with a dovetailed surface 87 mating with a correspondingly dovetailed surface 88 on table 11 and arranged to be

clamped in adjusted position thereon by means of a clamping gib 89.

In order that the truing apparatus may be accurately positioned for successively truing the operative face of a grinding wheel, the truing apparatus is placed in the work holders with the flange 52 engaging a locating surface 90 on the work head 34. This serves to locate the truing attachment in a definite position on the work table 11.

In order that the diamonds or truing tools 65 and 66 may be located in predetermined positions relative to the grinding wheel 14 for successive truing operations, it is desirable to provide a suitable locating means for accurately positioning the table 11 relative to the base 10. In the embodiment illustrated in the drawing, such a mechanism may comprise a stop 95 which is pivotally connected on a stud 96 on the base 10. The stop 95 is shown in full lines in its operating position. When this stop 95 is not required, it may be swung downwardly about its pivot 96 into a position 95a, as illustrated in dotted lines in Fig. 1. The table 11 is provided with adjustable dogs 97 and 98 which are adjustably clamped to table 11 by screws 99 and 100 respectively. The dogs 97 and 98 are each provided with an adjusting screw 101 and 102 respectively, which are arranged to engage the side faces of the stop block 95 to definitely locate the diamonds 65 and 66 in a predetermined position relative to the wheel 14.

As illustrated in Fig. 1, the table 11 has been moved toward the right, by means of the hand traverse wheel 43, so that the screw 101 of dog 97 is in engagement with the stop 95. This serves to locate diamond or truing tool 65 in a predetermined position for truing the left-hand side face of the grinding wheel 14. To true this side face of the wheel, the lever 75 is rocked from the full line position (Fig. 2) into position 75a which serves to pass the truing tool 65 in an arcuate path across a portion of the left-hand side face of grinding wheel 14, as viewed in Fig. 1.

After the left-hand side face of the grinding wheel has been trued, the table 11 may be moved toward the left, as viewed in Fig. 1, by means of the hand traverse wheel 43 until the stop screw 102 of dog 98 engages the stop 95 which serves to accurately position the diamond or truing tool 66 relative to the right-hand end face of the grinding wheel 14. By a similar rocking movement of the sleeve 51 by means of the lever 75, the diamond 66 may be then swung in an arcuate path across a portion of the side face of grinding wheel 14 to true its right-hand end face, as viewed in Fig. 1. It will be readily apparent from the foregoing disclosure that by adjustment of the screws 101 and 102, the position of the truing tools 65 and 66 may be varied so as to true the side faces of the grinding wheel 14 to the desired extent.

It is also desirable to provide the truing apparatus with a third diamond or truing tool 110 mounted in a holder 111 which is held in position on the sleeve 51 in an aperture in an outwardly extending boss 112 by means of a clamping screw 113. To true the peripheral face of the grinding wheel, the lever 75 is held in the full line position (Fig. 2) so that the diamond 110 engages the peripheral surface of the wheel 14 at a point lying substantially in the horizontal planes passing through the axes of the wheel and work holders. In this position of the parts, the table 11 may be traversed by means of the traverse wheel 43 to pass the diamond 110 across the peripheral face

of the wheel 14. The wheel 14 may be fed into the diamond 110 to the required extent by turning the feed wheel (not shown) to rotate the shaft 23 and cause a rotation of the feed screw and a forward feeding movement of the slide 16.

While truing the side faces of the grinding wheel, the grinding wheel is preferably separated from the diamond 110 so that when the diamond or truing tool 65 or 66 is in operative position, the diamond 110 will be out of contact with the peripheral surface of the wheel.

In the embodiment of this invention illustrated and described, three truing tools or diamonds have been illustrated, one for truing each side face 15 of the wheel and the third for truing the periphery of the wheel, it being understood that this mechanism is adapted for operation for truing a single surface of the wheel, that is, either the periphery or one side face of the wheel or any combination 20 of the operative faces of the wheel.

In the operation of this truing apparatus, the assembled truing apparatus is placed in operative position in the machine with the shaft 50 supported in the work holders 34 and 35. The attachment is then clamped in operating position with the collar 52 up against the locating portion 90 of the work holder 34. The stop 95 is then swung into an operating position and the table 11 traversed longitudinally into the position illustrated in Fig. 1 so that the left-hand side face of the grinding wheel may be trued, then the table 11 is traversed toward the left to position the truing tool 66 in operative position relative to the right-hand end face of the wheel 14 to true the same. The lever 75 is then held in engagement with stop 85 while the grinding wheel 14 is fed transversely to bring the peripheral face of the grinding wheel 14 into contact with the diamond or truing tool 110 and the table 11 is then traversed to pass tool 110 across the peripheral face of the wheel 14 to true the same. After this truing operation has been completed, the truing attachment may be readily removed from the machine by releasing the clamps 36 and 37 and lifting the attachment bodily from the work holders 34 and 35.

It will thus be seen that there has been provided by this invention a truing apparatus in which the various objects hereinabove set forth together with many thoroughly practical advantages are successfully achieved.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

Having thus described my invention, what I claim as new and desire to secure by Letters Patent is:

1. A grinding machine having a transversely movable rotatable grinding wheel, a longitudinally movable work table, means to traverse said table longitudinally, a rotatable work support thereon, and a truing apparatus therefor comprising a supporting member arranged to be held by said work support, a sleeve rotatably mounted on said member, a truing tool carried by said sleeve, means including a stop and dog mechanism to position said table to locate the truing tool in a predetermined position relative to the side face of the grinding wheel, and means to rock said sleeve to pass the truing tool in an arcuate path

across the side face of the grinding wheel to true the same.

2. A grinding machine having a base, a transversely movable rotatable grinding wheel, a longitudinally movable work table, means to traverse said table longitudinally, a rotatable work support thereon, and a truing apparatus therefor comprising a supporting member arranged to be held by said work support, a sleeve rotatably mounted on said member, a truing tool carried by said sleeve, a fixed stop on said base and an adjustable dog mounted on said table and arranged to locate the truing tool in a predetermined position with relation to the side face of the grinding wheel, means to rock said sleeve to pass the truing tool in an arcuate path across the side face of the grinding wheel, a second truing tool on said sleeve, and means including a second adjustable dog arranged to position said table to locate the second truing tool in a predetermined position with the opposite side face of the grinding wheel to true the opposed side face of the wheel.

3. A grinding machine having a base, a transversely movable rotatable grinding wheel, a longitudinally movable work table, manually operable means to traverse said table longitudinally, a rotatable work support thereon, and a truing apparatus therefor comprising a rotatable supporting member, a pair of truing tools adjustably mounted on said support in spaced relation to each other and arranged to true the opposite side faces of a grinding wheel, a stop on said base and a pair of opposed adjustable dogs on said table, and adjusting means on said dogs to precisely locate said table to successively position each of said truing tools in a predetermined position relative to the opposite side face of the grinding wheel, and means to rock said member, successively to pass the truing tools in arcuate paths across the opposed side faces of the grinding wheel to true the same.

4. A grinding machine having a base, a transversely movable rotatable grinding wheel, a longitudinally movable work table, a rotatable work support thereon, and a truing apparatus therefor comprising a supporting member arranged to be held by said work support, a sleeve rotatably mounted on said member, a pair of spaced radially extending projections on said sleeve, a truing tool adjustably mounted on each of said arms which are arranged to true the opposite side faces of the grinding wheel, means including a fixed stop and a pair of opposed adjustable dogs which are arranged to position said table to successively locate each of the truing tools in predetermined positions with relation to the opposed side faces of the grinding wheel, means to rock said sleeve to pass the truing tools in an arcuate path across the side face of the grinding wheel, a third truing tool adjustably mounted on said sleeve and arranged to true the periphery of said wheel when the table is traversed longitudinally, means to position said sleeve to locate said third truing tool in a predetermined position with relation to the wheel, and means to move the grinding wheel transversely toward the third truing tool while the table is traversed to true the peripheral face of the grinding wheel.

5. A truing apparatus for grinding machines comprising a supporting member having spaced aligning and supporting surfaces adjacent to the opposite ends thereof which are arranged to be supported on a pair of spaced opposed work holders, a sleeve rotatably mounted on said member,

a pair of spaced radially extending arms on said sleeve, a truing tool adjustably mounted in each of said arms and arranged to true the opposite side faces of a grinding wheel when the sleeve is rocked, a boss on said sleeve, and a truing tool adjustably supported by said boss which is arranged to true the peripheral face of said grinding wheel.

6. A truing apparatus for grinding machines comprising a supporting member having spaced aligning and supporting surfaces thereon adjacent to its opposite ends, a sleeve rotatably mounted on said member, a pair of spaced thrust collars on said supporting member which are arranged to locate said sleeve on said member, at least one of said collars being adjustable to take up the end thrust between said member and sleeve, a pair of spaced radially extending arms on said sleeve, a truing tool adjustably mounted on each of said arms and arranged to true the opposite side faces of a grinding wheel when the sleeve is rocked, and a manually operable lever adjustably mounted on said sleeve to rock said sleeve to pass the truing tools in an arcuate path

across the opposite plane side faces of the grinding wheel.

7. A truing apparatus for grinding machines comprising a supporting member having spaced aligning and supporting surfaces thereon adjacent to its opposite ends, a sleeve rotatably mounted on said member, a pair of spaced thrust collars on said supporting member which are arranged to locate said sleeve on said member, at least one of said collars being adjustable to take up the end thrust between said member and sleeve, a pair of spaced radially extending arms on said sleeve, a truing tool adjustably mounted on each of said arms and arranged to true the opposite plane side faces of a grinding wheel when the sleeve is rocked, a third truing tool on said sleeve which is arranged to true the peripheral face of said grinding wheel, and a manually operable lever adjustably mounted on said sleeve to rock said sleeve to pass the truing tools in an arcuate path across the opposite side faces of the grinding wheel.

GEORGE E. HULBERT.
